(57) **CLAIM**

The ornamental design for a range hood, as shown and described.

DESCRIPTION

FIG. 1 is a perspective view of a range hood showing our new design;

FIG. 2 is a front view of the range hood shown in FIG. 1;

FIG. 3 is a right side view of the range hood shown in FIG. 1, with the opposite side being a mirror image;

FIG. 4 is a top view of the range hood shown in FIGS. 1, 2 and 3;

FIG. 5 is a bottom view of the range hood shown in FIGS. 1, 2, 3, and 4; and,

FIG. 6 is a back view of the range hood shown in FIGS. 1, 2, 3, 4 and 5.

The broken line showing of environmental structure in FIGS. 1–6 is for illustrative purposes only and forms no part of the claimed design.
